CLAIM

The ornamental design for a panel for a handset, as shown and described.

DESCRIPTION

FIG. 1 is a front perspective view of a panel for a handset showing my new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken line showing of the remainder of the handset in FIGS. 1-8 is directed to environment, is for illustrative purposes only, and forms no part of the claimed design.

1 Claim, 5 Drawing Sheets
